TRANSFER ARM

Agnes J. Reeves Greer, Morgantown, W. Va.

Original application April 22, 1938, Serial No. 203,507. Divided and this application March 13, 1939, Serial No. 261,493

2 Claims. (Cl. 198—27)

The invention relates to transfer arms for use in apparatus for pickling coils of metal, of the general type of machines disclosed in my prior Patent No. 2,091,921, issued August 31, 1937, and 5 the present application is a division of my co-pending application for Pickling machines, Serial No. 203,507, filed April 22, 1938.

Machines of the general type referred to provide for the pickling of coils of metal supported 10 upon mandrels which are progressed through pickling and washing tanks, and the present invention relates to transfer arms for transferring the mandrels with the coils thereon from one tank to the next succeeding tank or for removing 15 the mandrel and coil from the last tank.

The object of the improvement is to provide arcuate surfaces upon the transfer arms in order to retard the movement of the mandrel across the transfer arms as the arms are operated.

20 A further object is to provide arcuate transfer arms with toothed tracks for engagement with sprockets or gears upon the mandrels.

The above objects together with others which 25 will be apparent from the drawing and following description, or which may be later referred to, may be attained by constructing the improved transfer arms in the manner illustrated in the accompanying drawing in which—

Figure 1 is a fragmentary top plan view of the 30 adjacent ends of two adjoining tanks of a pickling machine showing the improved transfer arms for removing the mandrel and coil from one tank and charging them into the adjacent tank;

Fig. 2, a side elevation of the parts shown in 35 Fig. 1;

Fig. 3, an enlarged fragmentary elevation partly in section of one of the transfer arms showing the curved toothed track thereon; and

Fig. 4, a further enlarged transverse sectional 40 view taken as on the line 4—4, Fig. 3.

Similar numerals refer to similar parts throughout the several views.

The discharge end portion of a pickling tank is indicated generally at 10, and the charging end 45 portion of the first washing tank is indicated at 11.

Rails 12 may be mounted above the pickling tank 10 forming a track upon which the mandrels 50 may be rotated as they are progressed forwardly along the tank so that the coils suspended thereon may be rotated through the acid in the tank as disclosed in my prior application above referred to.

The mandrel is in the form of a shaft 13 having a roller 14 fixed near each end thereof and

adapted to travel upon the corresponding rail 12.

A sprocket wheel or gear 15 may be fixed upon each end portion of the mandrel shaft 13 and is adapted to travel upon the toothed track as disclosed in my co-pending application Serial No. 5 203,507 of which this is a division.

Each sprocket wheel 15 is adapted to be engaged by an endless drive chain 16 located over sprockets 17 at opposite ends of the pickling tank and adapted to be continuously driven in unison 10 by means of the gearing indicated at 18 and the motor 19, drives the chains in the direction of the arrows shown in the drawing, the mandrel shaft being rotated and progressed forwardly along the 15 rails.

Near the discharge end of the pickling tank the rails 12 are preferably inclined downwardly as at 20 so that as the sprockets 15 of the mandrel become disengaged from the drive chains 16 the mandrel rolls down this incline and is deposited 25 in the hooks 21 of the transfer arms 22. These transfer arms are fixed in spaced relation upon a rocker shaft 23 arranged to be connected through suitable gearing indicated generally at 24 to a motor or other driving means 25.

The track portion 26 of each of the transfer arm hooks, which receives the ends of the mandrel shaft, and the toothed track portion 27 of each hook which engages the sprocket wheels 15 of the mandrel, are both concaved as best shown 30 in Fig. 3 so as to retard the movement of the mandrel as it rolls down the tracks of the hooks when the arms are moved over center and toward the discharge position.

The toothed track 27 may be in the form of a 35 section of sprocket chain, as indicated in Figs. 3 and 4 located in a channel member 28 connected at its ends to the hook 21 as by the bolts 29 and having a spaced pair of flanges 30 formed upon or fixed thereto, between which is located the 40 sprocket chain 27, the pins 31 of which may be located through the flanges 30.

In the operation of the apparatus the mandrel 13 with the coil C suspended thereon when received in the hooks of the transfer arms is moved 45 from the ends of the rails 12 and deposited in the curved guides 32 at the charging end of the first washing tank 11, riding down into the position shown in Fig. 2, where the mandrel shaft engages the rails 33 similar to the rails 12 above described and sprocket wheels of the mandrel shaft engage the drive chain 34 driven over sprocket wheels 35 in the direction of the arrow shown in Fig. 2 to convey the mandrels with the coils thereon through the first washing tank. 50 55

Although the transfer arms are shown only as located between the pickling tank and the first washing tank it should be understood that the same transfer arms are applicable for use between the first and second washing tanks or for removing the mandrels and coils suspended thereon from the second washing tank.

I claim:

1. Apparatus for handling a coil of metal including a mandrel upon which the coil is supported, and substantially T-shaped transfers arms pivoted at their inner ends and each having a hook at its outer end provided with a stop at each side and a concaved track portion extending en-

tirely along the hook from one stop to the other to receive the mandrel.

2. Apparatus for handling a coil of metal including a mandrel upon which the coil is supported, gear wheels upon the mandrel, substantially T-shaped transfer arms pivoted at their inner ends and each having a hook at its outer end provided with a stop at each side and a concaved track portion extending entirely along the hook from one stop to the other to receive the mandrel, and a concaved toothed track to engage one of said gear wheels.

AGNES J. REEVES GREER.
